HF-BF₃ TREATING OF NORMAL
ALKYLBENZENES

Arthur P. Lien, Highland, Ind., and David A. McCaulay, Chicago, Ill., assignors to Standard Oil Company, Chicago, Ill., a corporation of Indiana

Application November 13, 1953, Serial No. 391,876

11 Claims. (Cl. 260—668)

This is a continuation-in-part of our copending application Serial No. 306,648 filed August 27, 1952.

Broadly this invention relates to the transfer of n-alkyl groups, which are substituents of a benzene ring, without isomerizing the alkyl group. Particularly this invention relates to the preparation of di-n-propylbenzene by disproportionating mono-n-propylbenzene.

Some commercial demand has arisen for alkylbenzenes wherein the alkyl group contains three or more carbon atoms which have a normal configuration of the alkyl group; e. g., mono-n-propylbenzene is of interest as a source of β -methylstyrene. Various methods are known for the alkylation of benzene with n-alkyl halides to produce a mixture of mono-n-alkylbenzene and poly-n-alkylbenzene. However, attempts to convert said mono-n-alkylbenzene to the corresponding di-n-alkylbenzene invariably result in a substantial isomerization of the alkyl group. Thus preparation of di-n-alkylbenzene as presently known involves low yields and substantial loss to side reactants, such as iso-alkylbenzenes.

An object of the invention is the disproportionation of mono-n-alkylbenzene to the corresponding di-n-alkylbenzenes, particularly the meta-isomer thereof. A particular object is the preparation of di-n-propylbenzenes, particularly meta-di-n-propylbenzene, in high yield by the disproportionation of mono-n-propylbenzene. Other objects of the invention will become apparent in the detailed description.

In this process a normal alkylbenzene selected from the class consisting of propylbenzene, di-propylbenzene, butylbenzene and di-butylbenzene is contacted under substantially anhydrous conditions and in the substantial absence of reactive hydrocarbons with at least an effective amount of BF₃, preferably at least 0.5 mol per mol of alkyl groups present, and an amount of liquid HF at least sufficient to form a distinct acid phase, preferably between about 5 to 20 mols per mol of alkylbenzene; the contacting is carried out at a temperature between about -10° C. and about +100° C. for a time at least sufficient to produce an appreciable amount of poly-n-alkylbenzene; the HF and BF₃ are removed from the acid phase in order to recover the poly-n-alkylbenzene.

By operating for a sufficiently short time at a defined temperature and with a mono-n-alkylbenzene charge, the production of tri-normal alkylbenzene can be essentially eliminated.

The charge to the process contains normal alkylbenzenes selected from the class consisting of propylbenzene, butylbenzene and the corresponding di-alkylbenzenes. In order to obtain products containing only one particular alkyl substituent, the feed must contain only either propyl or butyl groups in the reactive component.

When the di-n-alkylbenzene is the only desired product, the charge should contain only the corresponding mono-n-alkylbenzene. When the yield of the tri-n-alkyl-

2

benzene is to be maximized, the charge should essentially contain only the corresponding di-n-alkylbenzene.

In addition to the alkylbenzene, the feed may contain non-reactive liquid hydrocarbons. It is to be understood that the term "non-reactive liquid hydrocarbons" is intended to mean those hydrocarbons which are liquid at operating conditions and which are inert to the action of the HF-BF₃ agent and do not participate in any reaction with the alkylbenzene charged. Examples of reactive hydrocarbons are olefins, xylene, di-ethylbenzene, ethyltoluene, ethylbenzene and isopropyltoluene. Examples of non-reactive hydrocarbons are: isopentane, butane and hexane. It is preferred that benzene be absent from the feed as its presence has an adverse effect on the degree of disproportionation obtained.

The process utilizes substantially anhydrous liquid hydrogen fluoride. The liquid hydrogen fluoride should not contain more than about 2 or 3% of water. Commercial grade anhydrous hydrofluoric acid is suitable for this process.

Under the conditions of the process, poly-alkylbenzenes form a complex containing 1 mol of BF₃ and, it is believed, 1 mol of HF. Therefore, at least enough liquid HF must be present to participate in the formation of the complex with the poly-alkylbenzene; in addition to this amount, sufficient liquid HF must be present to dissolve the complex which has been formed. In general, the presence of a distinct separate acid phase in the contacting zone indicates that at least the minimum requirement of liquid HF has been met. More than this minimum amount of liquid HF is desirable. Usually between about 3 and 50 mols of liquid HF are utilized per mol of secondary alkylbenzene charged to the process. It is preferred to operate with between about 5 and 20 mols of liquid HF per mol of alkylbenzene charged.

The process requires the presence of at least an amount of boron trifluoride sufficient to cause the disproportionation reaction to take place. While amounts of BF₃ as small as 0.1 mol per mol of normal alkyl groups charged will cause an appreciable amount of disproportionation to take place, it is desirable to operate with about 0.3 mol of BF₃. Still more BF₃ has a beneficial effect on the degree of the disproportionation reaction and as much as 5 or more mols may be used. When high purity meta-oriented poly-n-alkylbenzene is a desired product, it is preferred that at least 0.5 mol of BF₃ should be used per mol of alkyl groups charged. For example: with n-propylbenzene charge, at least 0.5 mol of BF₃ should be used per mol of n-propylbenzene; with di-n-propylbenzene charge, at least 1.0 mol of BF₃ should be used per mol of di-n-propylbenzene charged.

When the feed to the process contains poly-alkylbenzenes, for example, tri-n-propylbenzene, in addition to the defined alkylbenzene, the BF₃ usage should be, in addition to that set out above, 1 mol per mol of said poly-alkylbenzene.

The process may be operated with two liquid phases present in the contacting zone. At high BF₃ usages, a gas phase may also be present in the contacting zone. The two liquid phases will be spoken of herein as the raffinate phase and the acid phase. The acid phase consists of liquid HF, BF₃, complex and physically dissolved hydrocarbons. The raffinate phase may be n-alkylbenzene in excess of that amount taken into the acid phase, or may be a mixture of n-alkylbenzene and inert hydrocarbons, or may be principally inert hydrocarbons. In the absence of substantial amounts of inert hydrocarbons, the amount of raffinate phase is dependent upon the amount of BF₃ utilized. When using at least about 0.5 mol of BF₃ per mol of n-alkylbenzene, and in

the substantial absence of inert hydrocarbons, all or virtually all the alkylbenzene will be taken into the acid phase either in the form of a complex or in solution. The presence of HF-BF₃-poly-alkylbenzene complex in liquid HF very greatly increases the solubility of the liquid HF for aromatic hydrocarbons and increases slightly the solubility of paraffinic hydrocarbons.

The presence of a raffinate phase consisting principally of inert hydrocarbons, such as benzene and paraffins, has an adverse effect on the degree and direction of conversion of the n-alkylbenzene charged, even though theoretically sufficient BF₃ is present to complex all of the poly-n-alkylbenzene formable from the n-alkylbenzene charged. A substantial amount of the n-alkylbenzene will remain in the raffinate phase, even when using somewhat more than 0.5 mol of BF₃ per mol of n-alkyl groups charged. The alkylbenzene in the raffinate phase does not undergo a rearrangement reaction to any significant extent, even under conditions of good agitation. (The presence of dissolved inert hydrocarbons in the acid phase does not appear to have any adverse effect on the degree or direction of the rearrangement reactions.)

In order to maximize the yield of conversion products, and to produce a di-normal alkylbenzene product fraction consisting essentially of 1,3-di-normal alkylbenzene, i. e., the meta isomer, it is preferred to operate under conditions which form a single essentially homogeneous liquid phase in the contacting zone. A single essentially homogeneous liquid phase is attainable with a feed containing as much as three volume percent of paraffinic hydrocarbons. Large amounts of benzene may be dissolved in the acid phase, as much as 1 mol or more, per mol of complexed poly-alkylbenzene, depending on the amount of complex in the acid phase. (It is to be understood that a separate gaseous BF₃ phase may also be present, but it is preferred that a minimum of free space be present in the contacting zone and that sufficient pressure be maintained to insure that essentially all the BF₃ is either in the complexed form or is in physical solution in the acid phase.)

The degree and direction of the disproportionation reaction are also determined by the temperature of contacting and the time of contacting; a definite relationship exists between the temperature, time and desired disproportionation products. At temperatures much below about -10° C. no appreciable disproportionation takes place even at contacting times of several hours. At temperatures of about +100° C., side reactions such as cracking occur and the direction of the disproportionation changes; gas and a wide boiling range product mixture are obtained.

The contacting time has an important effect on the course of the rearrangement reactions. At least sufficient time must be provided at the particular temperature of operation in order to obtain an appreciable amount of disproportionation products. As the contacting time is increased, at a constant temperature, the amount of disproportionation product increases. The disproportionation reaction appears to produce the di-alkylbenzene as the first product. Dependent upon the temperature, a finite period of time elapses between the appearance of detectable amounts of the di-alkylbenzene product and the appearance of the tri-alkylbenzene product. The lower the temperature of operation, the longer the time elapsed before the appearance of an appreciable amount of the tri-derivative.

With increasing contacting time, at constant temperature, the amount of tri-alkylbenzene product gradually increases at the expense of di-secondary alkylbenzene formed. Gradually the amount of the tri-derivative increases and eventually the tri-derivative continues to increase with simultaneous disappearance of the di-derivative. At higher temperatures and prolonged contacting times, the reaction product mixture contains the

tri-derivative as the predominant disproportionation reaction product. However, at prolonged contacting times at high temperatures, the cracking reaction goes on at the expense of the poly-alkylbenzene and the yield of poly-alkylbenzene decreases.

The disproportionation reaction can be controlled, within experimental error, to produce di-alkylbenzene as essentially the only poly-alkylbenzene product, by suitably adjusting the time and temperature of contacting. 10 The lower the temperature of contacting, the longer the contacting time permissible to avoid the formation of detectable amounts of the tri-derivative.

Normal propylbenzene.—The propylbenzenes can be disproportionated at temperatures as high as about 15 +100° C. By operating at times of 2 to 3 minutes, cracking and side reactions can be reduced to some extent. The desirable maximum temperature of operation is about +75° C. and the maximum time of contacting at this temperature is about 30 minutes. By operating 20 for prolonged times, it is possible to obtain a significant amount of disproportionation at temperatures as low as -10° C. or even somewhat lower. At about -10° C. the minimum contacting time should be at least 60 minutes.

25 At the higher temperatures mono-n-propylbenzene disproportionates to a mixture of di-n-propylbenzene and tri-n-propylbenzene. When a mixture of poly-n-propylbenzene is suitable, the process is preferably carried out at a temperature between about +20° and about +75° C.; the contacting times should be between about 5 minutes and 6 hours, the longer times corresponding to the lower temperatures.

30 A reaction product mixture containing the di-n-propylbenzene as essentially the only poly-n-alkylbenzene can be obtained by operating for short contacting times at elevated temperatures, for example, about 5 minutes at +60° C. Longer times may be tolerated at the lower temperatures, for example, at +20° C. about 3 hours.

Normal butylbenzene.—The n-butylbenzenes undergo 35 cracking and other side reactions more readily than the n-propylbenzenes. The upper temperature limit for n-butylbenzene operation is about +90° C. at very short contacting times. The desirable upper limit of operation is about +60° C. and at this temperature the maximum contacting time is about 60 minutes. The practical lower limit for the disproportionation of n-butylbenzenes is about 0° C.; at this temperature, a contacting time of at least about 60 minutes is needed to produce a significant amount of disproportionation.

40 When a product containing both di-n-butylbenzene and tri-n-butylbenzene is suitable, the mono-n-butylbenzene disproportionation reaction is preferably carried out at a temperature between about +20° and +60° C. at contacting times between about 20 minutes and 6 hours, the longer times corresponding to the lower temperatures.

45 The formation of the tri-n-butylbenzene can be avoided somewhat more readily than in the corresponding n-propylbenzene reaction. When the di-n-butylbenzene is essentially the only poly-n-butylbenzene product, the 50 reaction is carried out at a temperature between about +20° and +60° C. for a time between about 5 minutes and about 3 hours, the longer times corresponding to the lower temperatures.

Di-n-alkylbenzene.—When the mono-n-alkylbenzene 55 is the charge to the disproportionation process, an upper limit on the yield of the corresponding tri-n-alkylbenzene appears to exist. Even at high temperatures a considerable amount of the corresponding di-n-alkylbenzene is present in the reaction product mixture. The yield of the tri-n-alkylbenzene can be maximized by using the corresponding di-n-alkylbenzene as the feed. By operating at higher temperatures, it is possible to produce a reaction product mixture that consists substantially entirely of the tri-n-alkylbenzene and some tetra-n-alkylbenzene. By operating at lower temperatures and shorter 60

times the yield of the corresponding tetra-n-alkylbenzene can be minimized. In general, the temperature of contacting for the di-n-alkylbenzene charge is preferred to be between about +20° and about +60° C. and the times of contacting are between about 5 minutes and 3 hours, the longer times corresponding to the lower temperatures.

Even when using smaller amounts of BF_3 , the predominant di-n-alkylbenzene product is the 1,3-di-n-alkylbenzene, i. e., the meta isomer. The use of 0.5 mol of BF_3 gives essentially pure 1,3-di-n-alkylbenzene as the di-n-alkylbenzene product. By careful control of the contacting time it is possible to produce a di-n-alkylbenzene product fraction which is, within the error of the analytical procedure, pure 1,3-di-n-alkylbenzene.

Under the conditions of operation described above, the tri-derivative is essentially pure 1,3,5-tri-n-alkylbenzene, i. e., the meta-oriented symmetrical configuration.

When the charge to the di-n-alkylbenzene disproportionation process consists of mixtures of the meta isomer and at least one other isomer, which other isomer is present in substantial amounts, the acid phase contains a reaction product mixture wherein the di-n-alkylbenzene fraction is enriched with respect to the meta isomer. When operating under essentially single liquid phase conditions and with at least 1 mol of BF_3 per mol of di-n-alkylbenzene charged, the reaction product mixture contains essentially pure meta di-n-alkylbenzene as the n-alkylbenzene component, i. e., the ortho and/or para isomers are isomerized to the meta isomer.

By operating at very low temperatures, e. g., -20° C., and short times, or, at moderate temperatures, e. g., +15° C., in the presence of added benzene, it is possible to isomerize the ortho and para di-n-alkylbenzenes essentially completely to the meta isomer, without a substantial amount of disproportionation reaction taking place.

The invention is limited to the HF-BF_3 treatment of propylbenzene and butylbenzene because successful treatment of the pentylbenzene requires very different operating conditions.

The reaction product mixture may be recovered from the acid phase by various methods. Probably the simplest procedure and one most suitable for laboratory work consists of adding the acid phase to crushed ice; or the acid phase may be contacted with cold aqueous alkaline solution, such as sodium hydroxide, potassium hydroxide and ammonia. It is desirable to prevent rearrangement reactions by the use of a cold aqueous reagent.

The hydrocarbons originally present in the acid phase appear as an upper oil layer above a lower aqueous layer. The upper oil layer may be separated by decantation and may be treated with dilute aqueous alkaline solution to remove any remaining HF and BF_3 occluded therein.

Both HF and BF_3 are relatively expensive chemicals and it is desirable in an economic process to recover these and to recycle them for reuse in the process. The HF and the BF_3 may be readily removed from the acid phase by heating the acid phase or by applying a vacuum thereto. The HF and BF_3 distill overhead and may be recovered for reuse in the process. When di-alkylbenzenes and/or tri-alkylbenzenes are the principal complex-forming hydrocarbons, the complex may be decomposed at relatively low temperatures by the use of vacuum distillation. The tetra alkylbenzene and higher alkylbenzene complexes are stable and must be heated to relatively high temperatures, for example, 150° C. or more in order to decompose the complex.

The rearrangement reaction proceeds from the time that the complex is formed until the complex is decomposed, assuming that a suitable temperature exists. When it is desired to produce essentially only one rearrangement reaction product, for example, meta di-n-propylbenzene from n-propylbenzene, it is necessary to take into account the total time elapsing from the time that the complex has been formed till the time that it has been de-

composed in the distillative decomposition procedure. Thus, when using distillative decomposition procedure, it is necessary to consider the residence time of the complex in the decomposing zone as a part of the contacting time. Also, it is necessary to consider the temperature maintained in the decomposing zone when a particular product or a particular ratio of products is desired. The distillative decomposing zone may be operated at temperatures as low as about -20° C. by the use of high vacuum therein. It is preferred to operate at temperatures of +60° C., or lower when the di-derivative is the desired product.

EXAMPLES

15 The results obtainable by the invention are illustrated by severals examples set out below. The runs were carried out using a carbon steel reactor provided with a 1725 R. P. M. stirrer. The order of addition of materials to the reactor was: (1) n-alkylbenzene of CP quality (2) 20 commercial grade anhydrous liquid HF and (3) commercial grade BF_3 . The contents of the reactor were agitated during the addition of the HF and BF_3 ; the agitation was continued while the reactor was brought to the desired contacting temperature and maintained during 25 the contacting time. The contents of the reactor were withdrawn into a vessel filled with crushed ice. An upper aqueous hydrocarbon layer formed above a lower aqueous layer. The hydrocarbon layer was decanted and washed with dilute ammonium hydroxide solution to 30 remove HF and BF_3 . The neutral hydrocarbons were water-washed to remove traces of ammonium hydroxide.

The reaction product hydrocarbons were fractionated in a laboratory distillation column provided with about 30 theoretical plates. Each product fraction was analyzed by a combination of boiling point, specific gravity, refractive index, and ultraviolet and infrared technique.

The results of these runs are set out in the table. Test 1 was carried out under conditions such that two liquid phases were present in the reactor when the contents were withdrawn. The raffinate phase contained 76 weight percent of the total reaction product mixture and the extract phase contained 24 weight percent. The results show that all the tri-n-propylbenzene remained in the acid phase and about half of the di-n-propylbenzene remained in the acid phase. This run illustrates the fact that even at low temperatures, the use of small amounts of BF_3 tends to produce appreciable amounts of the tri-derivative.

In this test and all tests, the di-derivative recovered from the acid phase consisted of, within analytical error, the meta isomer and the tri-derivative consisted, within analytical error, of the 1,3,5-tri-derivative.

Test 2 was carried out at a temperature the same as in test 1. However, a large excess of BF_3 was present. This test shows that even with a large excess of BF_3 and at a 30 minute time—10 minutes longer than the total time in test 1—no tri-derivative was formed. The percent disproportionated in tests 1 and 2 also shows the favorable influence of a single essentially homogeneous phase in the reactor and longer contacting time.

Test 5 shows that at a temperature of +103° C. a considerable amount of cracking and side reactions have occurred, as evidenced by the large yield of bicyclics and higher boiling material.

Test 4, which was carried out at +50° C., gave a 45% yield of the di-propylbenene—no tri-propylbenene—at an overall percent disproportionation of 87%. These two tests show that operation at too high a temperature not only results in the predominance of the tri-derivative, but also results in a reduction in the overall yield of the di-propylbenzene and tri-propylbenzene.

Tests 3 and 6 were carried out using n-butylbenzene as the charge. Test 3 shows that the n-butylbenzene disproportionates much more slowly than does n-propylbenzene. In test 2, 49% of the n-propylbenzene was

disproportionated, whereas under the same conditions in test 3 only 15% of the n-butylbenzene was disproportionated.

Test 6 shows that n-butylbenzene undergoes side reactions to a greater extent at elevated temperatures than does n-propylbenzene. Thus, in test 6, all the di-derivative disappeared and only 9% of the tri-derivative was present whereas about 20% of the total reaction product mixture consisted of the products of side reactions. On the other hand, test 5 shows that under the same conditions, n-propylbenzene gives a 25% yield of poly-propylbenzene and only half as much side reaction product as n-butylbenzene.

Table

Test No.	1	2	3	4	5	6
Charge:						
n-alkylbenzene, type	propyl	propyl	propyl	propyl	propyl	butyl

ILLUSTRATIVE EMBODIMENT

The annexed figure, which forms a part of this specification, shows an illustrative embodiment of a method of carrying out the invention to produce essentially pure 1,3-di-n-propylbenzene by disproportionating n-propylbenzene which had been obtained by alkylating benzene with propylchloride under mild conditions. The figure is schematic and many items of equipment have been omitted, such as pumps, valves, etc., as these may be readily added thereto.

Feed from source 11 is passed by way of lines 12 and 13 into heat exchanger 14. From exchanger 14 the feed, recycled n-propylbenzene, are passed by way of line 16 into line 17.

Anhydrous liquid hydrogen fluoride, 9 mols/mol of charge, is passed from line 26, through heat exchanger 27 and line 28 into line 17. Heat exchangers 14 and 27 raise the temperature of the charge and the liquid HF to a temperature of about +40° C. This temperature is about 10° C. lower than the desired reaction temperature of +50° C.

The contents of line 17 are introduced into mixer 31 which is provided with heat exchanger means 32. BF₃, 0.6 mol/mol of charge, from line 29 is introduced into mixer 31. Mixer 31 is an apparatus able to rapidly intermingle the charge, liquid HF and BF₃. The heat exchanger means 32 withdraws the heat given off by the complex formation and prevents the temperature at the discharge end of mixer 31 rising above +50° C.

An acid phase consisting of liquid HF, dissolved complex, hydrocarbons and BF₃ is discharged from mixer 31. About 200 p. s. i. g. of pressure are maintained on the system to keep the excess BF₃ in the acid phase. The mixture is passed from mixer 31 by way of line 33 into reactor 34.

Reactor 34 is provided with heat exchanger means 36 and 37. To insure the maintenance of a substantially uniform temperature of +50° C. throughout the reactor, reactor 34 is provided with baffles 38a, 38b and 38c and motor driven agitator means 39.

A single acid phase is withdrawn from the top of reactor 34 and is passed by way of line 41 into decomposing zone 43. The rearrangement reaction starts as soon as the HF, BF₃, and n-propylbenzene are mixed and continues until the HF and BF₃ are distilled from the acid phase. Therefore, the contacting time is measured as the time in mixer 31, reactor 34 and part of the total time in decomposing zone 43. In this embodiment, a total time of about 20 minutes is utilized. Under these conditions only a very slight amount of tri-propylbenzene is formed.

Decomposing zone 43 is provided with internal heater 44 and some fractionation means, not shown. The tem-

perature of +50° C. at about atmospheric pressure in zone 43 is high enough to readily decompose the HF-BF₃ complexes but not high enough to cause appreciable further disproportionation.

HF vapor and BF₃ gas are withdrawn from zone 43 and passed by way of line 47 into heat exchanger 48. In heat exchanger 48 the HF vapors are condensed and a liquid-gas stream is passed by way of line 49 into gas separator 51. BF₃ is withdrawn from gas separator 51 and is recycled by way of lines 53 and 29 to mixer 31. Make-up BF₃ is introduced from source 56 by way of valved line 57 into line 53. Liquid HF is recycled by way of lines 61 and 26. Make-up HF is introduced from source 62 by way of valved line 63 into line 61.

The bottoms fraction from decomposing zone 43 consists of n-propylbenzene, di-n-propylbenzene, benzene and a very slight amount of tri-propylbenzene. The bottoms fraction is withdrawn and introduced by way of line 71 into fractionation zone 72, shown schematically herein. A benzene fraction is withdrawn to storage by way of line 74. A product fraction consisting of essentially pure 1,3-di-n-propylbenzene is passed to storage by way of line 76. A bottoms fraction of tri-n-propylbenzene is withdrawn by way of line 78. Unconverted n-propylbenzene is withdrawn from zone 72 and recycled to the reaction zone by way of line 79, etc.

Thus having described the invention, what is claimed is:

1. A process for the production of poly-n-alkylbenzenes, which process comprises contacting, under substantially anhydrous conditions, a feed consisting essentially of normal alkylbenzene selected from the class consisting of propylbenzene, di-propylbenzene, butylbenzene, di-butylbenzene, mixtures of said propylbenzenes and mixtures of said butylbenzenes, with at least enough liquid HF to form a distinct separate acid phase and with at least about 0.3 mol of BF₃ per mol of alkyl groups in said feed at a temperature between about -10° and +100° C. for a time at least sufficient to form an appreciable amount of poly-n-alkylbenzene and recovering poly-n-alkylbenzene from said acid phase.

2. The process of claim 1 wherein said liquid HF is present in an amount between about 3 and 50 mols per mol of alkylbenzene in said feed.

3. The process of claim 1 wherein said BF_3 is present in an amount of at least 0.5 mol per mol of alkyl groups in said feed. 5

4. The process of claim 1 wherein said temperature is between about $+20^\circ$ and $+60^\circ$ C.

5. A process which comprises contacting, under substantially anhydrous conditions, a feed consisting essentially of mono-normal-propylbenzene, with between about 5 and 20 mols of liquid HF and at least about 0.5 mol of BF_3 , respectively, per mol of said propylbenzene, at a temperature between about -10° C. and about $+75^\circ$ C. for a time sufficient to obtain at least an appreciable amount of poly-n-propylbenzene, and removing HF and BF_3 to recover a mixture of hydrocarbons containing said poly-n-propylbenzene. 10 15

6. The process of claim 5 wherein said temperature is between about $+20^\circ$ C. and about $+75^\circ$ C. and said time is between about 5 minutes and 6 hours, the longer times corresponding to the lower temperatures. 20

7. A process for preparing meta-di-n-propylbenzene, which process comprises contacting, under substantially anhydrous conditions, a feed consisting essentially of mono-n-propylbenzene with between about 5 and 20 mols of liquid HF and between at least 0.5 and about 3 mols of BF_3 , respectively, per mol of said propylbenzene, at a temperature between about $+20^\circ$ C. and about $+60^\circ$ C. for a time such that m-di-n-propylbenzene is essentially the only disproportionation product, and recovering essentially pure meta-di-n-propylbenzene from the reaction product mixture. 25 30

8. The process of claim 7 wherein the time is between

about 5 minutes and 3 hours, the longer times corresponding to the lower temperatures.

9. A process which comprises contacting, under substantially anhydrous conditions, a feed consisting essentially of mono-normal-butylbenzene, with between about 5 and 20 mols of liquid HF and at least about 0.5 mol of BF_3 , respectively, per mol of said butylbenzene, at a temperature between about 0° C. and $+60^\circ$ C. for a time sufficient to obtain at least an appreciable amount of poly-n-butylbenzene, and removing HF and BF_3 to recover a mixture of hydrocarbons containing said poly-n-butylbenzene.

10. The process of claim 9 wherein said temperature is between about $+20^\circ$ C. and about $+60^\circ$ C. and said time is between about 20 minutes and 6 hours, the longer times corresponding to the lower temperatures.

11. A process for preparing meta-di-n-butylbenzene which process comprises contacting, under substantially anhydrous conditions, a feed consisting essentially of mono-n-butylbenzene with between about 5 and 20 mols of liquid HF and between at least 0.5 and about 3 mols of BF_3 , respectively, per mol of said butylbenzene, at a temperature between about $+20^\circ$ C. and about $+60^\circ$ C. for a time between about 5 minutes and 3 hours, the longer times corresponding to the lower temperatures, and removing HF and BF_3 to recover a reaction product mixture containing meta-di-n-butylbenzene as essentially the only poly-alkylbenzene therein.
